Primary Examiner — John Windmuller*Assistant Examiner* — Steven Czyz(57) **CLAIM**

The ornamental design for a cane with light, as shown and described.

DESCRIPTION

FIG. 1 is a right side view of a cane with light showing my new design, a left side view being a mirror image thereof; FIG. 2 is a front view of the cane with light; FIG. 3 is a rear view of the cane with light; FIG. 4 is a top view of the cane with light; and, FIG. 5 is a bottom view of the cane with light. The broken lines depict portions of the article that form no part of the claimed design.

1 Claim, 3 Drawing Sheets(56)
